UNITED STATES PATENT OFFICE.

DONALD I. BUCHANAN, OF NEW YORK, N. Y.

MOVIE GAME.

Application filed July 13, 1927. Serial No. 205,387.

This invention relates to a game and more particularly to that type of game wherein an education as well as amusement will be derived from playing it.

The usual run of games involves the reaching of a certain goal or point merely for the sole purpose of having one player declared victor over the contesting player. While this is an object of the present invention, it also has for its main object the enlargement of the mental faculties by schooling the individual players in the art or science of story or play writing.

To this end the invention is found to reside in a game and the method of playing the same, whereby a well developed story in narrative form may be evolved from the playing of the game to the amusement and recreation of those interested. Also, the invention aims to impress and imprint upon the minds of the players the essentials of narrative or story technique which will instruct them in contriving schemes and arranging plots in story writing.

The invention has for a further object to provide a plot-contriving game having general structural divisions of a story, each division having a plurality of otherwise unrelated descriptive matters whereby a player or players may be enabled to weave a story from a chance selection of any one of the descriptive matters from each and all of the divisions when collected in their sequential order.

A still further object of the invention is to provide a game board with a plurality of columns corresponding in number to either the general or special structural divisions of a plot, each column being divided into spaces or blocks individually containing several corresponding essential elements or data relating to the particular structural division, and which when combined with any of the spaces or blocks of the component structural divisions will provide the essentials of a narrative and produce a well rounded story having the requisite technique.

The invention further resides in the provision and arrangement of a plurality of story-divisions each including a series of phrases, words or emblems to be selected by a chance device, or the like, for weaving a story the character of which is indeterminate at the start of the game so that the player's interest will be held throughout every move or play of the game. It is also an

object of this invention to provide hazards or obstacles to be encountered by chance and thereby enable one player to gain an advantage over his opponent and permit him to first complete his story.

A still further object of the invention is to provide a novel form of chance device by which the plays of the game may be indicated at random.

In the drawings,

Fig. 1 is a perspective view, partly broken away, showing the preferred embodiment of the present invention; and

Fig. 2 is a detailed perspective of a simple form of game piece utilized in playing the game.

In proceeding in accordance with this invention I have utilized the technique of a story and divided it into a series of what might be termed structural divisions which will be found common to nearly all if not all of the stories or plays written. The number of structural divisions may be augmented if desired by other predetermined or special divisions special to the type or character of story written whether or not it be a play, plot or the like. In carrying this idea forward, I have utilized the structural divisions of a story, either general or special, as the main headings under which are grouped suitable emblems, words or phrases characteristic or descriptive of the particular title of the structural division but comprising the essentials of several stories or narratives. To avoid any hard or fast rule which might detract from the amusement or fun side of the game, I have provided a device by which, from a chance selection or a selection at random, the different emblems, words or phrases so selected will produce sentences with correct syntax and the sentences will follow in sequential order for the formulation or weaving of a complete story.

The game may assume different forms but in its preferred embodiment, the structural divisions and their components constitute the playing surface of a game board. As shown in Fig. 1 this game board 1, which is foldable for convenience, is provided with a transversely extending series of columns 2 divided into rows of spaces or blocks 3 registering with certain indicia in the vertical, marginal columns 4. Each column 2 may be suitably indexed or designated by some character, such as the alphabetical notations A, B, C, D, E, F, G, H, I, J, and K, indi-

cated in Fig. 1, and also provided with headings 5 appropriate for the structural divisions of a story. The spaces or blocks 3, underlying each heading, contain data or 5 words which are appropriate for that particular heading. Each space will contain an essential element for a story corresponding to the heading, and the several spaces of each column will therefore contain a group 10 of such essential elements, differing individually but all bearing a like relation to the heading. For instance, the first column "A," referring to "location," has in each block or space an essential element or words 15 descriptive of a place or location at which the indeterminate story begins; the second or "B" column contains the appropriate element or words relating to the heading "time"; and the third or "C" column contains 20 names of boys who will take the part of the "hero." The numbers appearing in the marginal columns 4 indicate the order in which the players will proceed after the initial play, which initial play may be decided as desired or according to the rules of 25 the game.

Along one edge of the game board, preferably the upper edge, is provided a border or marginal space in which the rules and 30 title of the game may be displayed. For determining the moves or the plays of the different players a game apparatus is utilized by which the individual players will have their particular plays governed by chance. 35 While any suitable chance device may be employed, it is preferable to utilize a spin device such as indicated at 6 wherein the spin member may be pivotally secured directly to the game board within the marginal space 7 as indicated at 8. Ordinarily 40 these spin devices embody an arrow, but in the present instance I have substituted a spin disc or wheel having a sight opening 9 which presents to view one of a circular series of ordinals which are otherwise concealed by the body of the disc 6. In forming 45 this sight opening the material struck from the disc is turned upwardly to provide a spur or abutment 10 which the player may use as a means to spin or rotate the disc, such as by snapping his finger thereagainst. 50

Any suitable game pieces may be provided, although for purposes of illustration a simple disc 11 is provided. Each player's 55 discs will be colored or otherwise distinguishable from his opponents, and each player will have a number of discs corresponding in number to the columns 2. Thus, in the present showing each player will have eleven discs or "men" corresponding in 60 number to the eleven columns A, B, C, D, E, F, G, H, I, J, and K.

In playing the game, each player in turn 65 will spin the disc or wheel 6 and whatever number the opening 9 displays, when it

comes to rest, will indicate the space or block 3 of the first column in which he will place his game piece or "man." Thus, in Fig. 1, the number 2 is displayed through the sight opening 9 which indicates to that 70 particular player that he is to place one of his men 11 in column A two spaces down, or in row 2. In the present showing each column is provided with 9 spaces and therefore the marginal columns 4 are provided 75 with numbers 1 through 9 which not only facilitate the positioning of the men in the indicated spaces but also determine the order of the players for the next succeeding play. Depending upon the rules of the 80 game, either the low or the high man in column 1 will then first proceed with his second spin, to be followed by the other players in their order. Thus, if it be decided that the low man will have the preference on his next shot, then the player who has his man in space 1 of column A, or nearest such location, will be entitled to proceed first on the second play. Then if 85 the player who first played on his second turn should have the ordinal 9 show up through the sight opening 9, and thereby cause his man to be placed in space 9 of column B, it will be observed that the order 90 of play will be changed for the next or third play. By reasons of the chance selection of the spaces it is obvious that the order of play will or may constantly change.

The rules may provide certain hazard elements or obstacles, such as is indicated at 104 12, for penalizing the player. If a player should fall into a such a hazard space 12 he may, according to the rules, be required to start over again in column A, or lose one or more turns, or the like. Other rules may 105 be provided in increase the amusement side of the game.

According to the rules of the game the first player who reaches column K will be called "director" and he will have the advantage over the other players who must also complete their plays. Such advantage may involve the acting by the loser of the story which his game pieces evolves or produces. For instance, assuming that the 110 victor or director has removed his men from the board and that the loser's game pieces are arranged as indicated by the dotted showing of the discs across the board in Fig. 1, the director will then lift up his opponent's men in sequential order beginning with column A and read the woven story or plot. In the example, the several elements of his opponent's story will read as follows: "In front of a theater—as the clock struck 12— 115 William—a successful novelist—was nearly killed by a car driven by—Imogene the orphan daughter of a rich banker. Months afterward—the heroine was abducted and held for ransom. When the hero found the 120 125 130

clue—a wild chase started—through the nearby hills and—the villian and his gang were finally captured after a desperate battle etc."

5 While the game is exceedingly amusing and full of fun, it will be observed that the individual players are having impressed upon their minds certain structural divisions of stories which will have their effect in 10 training each player in the essentials of story or play writing and will enable him to analyze and follow the line of thought in books which he may read.

The body of the game board may be replaceable, with or without the headings, so 15 that structural divisions of stories of different characters may be arranged to suit a particular occasion, and in which event the body may comprise what is termed a "filler" 20 to be detachably secured as by means of clips 13. These "fillers" may comprise several playing surfaces preferably embodied in the form of a book or a series of pages 14. Each playing surface may have the subject 25 matter appropriate for a particular line of stories; one surface comprising structural divisions relating to western stories, another to mystery stories, etc.; or one playing surface may relate to juvenile stories 30 and another to adult stories so that the game will be readily adaptable to the entire family and for parties both old and young.

To facilitate the description of this invention, the term "story" is used to include 35 a plot, play, sentence or other narrative; the term "structural divisions" to include the essential or special elements or parts of a sentence or story; and the term "elements" 40 to include the several parts under each heading or division.

I claim as my invention:

1. A game comprising a series of columns containing the corresponding structural divisions of the essential elements for 45 several stories, each column being divided transversely into spaces for containing the individual elements, and means for selecting at random a space from each column for weaving a story from the selected elements, 50 the selected elements forming in themselves a complete story.

2. A game board having a series of headings indicating the structural divisions of a story, a plurality of elements under each 55 heading, each associative with any element under the next adjacent heading to weave and continue without modification, a portion of a complete story, the several elements under each heading being appropriate for the 60 heading but unrelated to the companion elements under the particular heading, the object of the game being to select at random an element from under each heading and group them to formulate a story therefrom.

65 3. A game comprising a board divided

into columns of spaces, each column being designated as a structural division of a story, and each space of each column containing data appropriate for the particular columnar designation, and associative with the 70 data in any space of the next adjacent column to form and complete a connected thought therewith, the data in any space bearing a definite narrative relation to the data in any space in the next adjacent column. 75

4. A game comprising a board divided into columns of spaces, each column being designated as a structural division of a story, and each space of each column containing data appropriate for the particular columnar designation, means for selecting one space from each column at random to 80 formulate a story, and means for temporarily marking the selected spaces until the 85 selection has been completed.

5. A story-plotting game comprising a board divided into columns of essential elements for a story, each column being designated as a structural division of a story, the object of the game being to select by chance 90 an element from each column and weave a story therefrom, certain of said columns containing hazard elements for penalizing any 95 player selecting any of the latter elements.

6. A story-plotting game comprising a series of columns designated according to the structural division of a story, said columns being divided into spaces forming a plurality of rows of spaces, each row intersecting each column and appropriately designated, each space containing data descriptive of the particular structural division, and a chance device having designations corresponding to the row designations by which 100 the several spaces of the game board may be chance-selected for formulating a story of indeterminate makeup at the start of the game, the selection of any one space from each and all of said columns producing in its 105 entirety a complete story.

7. A plot-contriving game comprising a series of structural divisions, each containing a group of corresponding but individually dissimilar essential elements, each element being associative, according to story technique, with elements of other structural divisions, to form in their entirety a complete story, said divisions being arranged in sequence, and a chance-selecting device for 110 promiscuously making selections of the elements from the sequentially arranged divisions for forming a complete story of originally indeterminate character.

8. A plot-contriving game comprising a board having appropriately designated index parts, a removable filler constituting the playing surface and having plot-structural divisions related to said index parts, said 115 filler being replaceable by another filler 120

125

whereby differently characterized plots may be contrived to suit the players.

9. A plot-contriving game comprising a board having a plurality of hingedly connected playing surfaces, only one of which is exposed at a time for playing, each playing surface containing sequentially arranged structural divisions individually embodying groups of essential elements to be selected by 20 plays of the players, the elements of one playing surface relating to an entirely different type of story from the elements of another playing surface whereby the players may determine the general type of an otherwise initially indeterminate story before 25 play.

10. A plot-contriving game comprising a

board having a plurality of hingedly connected playing surfaces, only one of which is exposed at a time for playing, each playing surface containing sequentially arranged structural divisions individually embodying groups of essential elements to be selected by 20 plays of the players, the elements of one playing surface relating to an entirely different type of story from the elements of another playing surface whereby the players may determine the general type of an otherwise initially indeterminate story before 25 play, and a chance-selecting device arranged on the board to enable the players 30 making selections of the elements at random.

DONALD I. BUCHANAN.
